(57) CLAIM

The ornamental design for a case for stylus pen, as shown and described.

DESCRIPTION

FIG. 1 is a front and right side perspective view of a case for stylus pen, showing my new design;

FIG. 2 is a rear and left side perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is a use state perspective view thereof; and,

FIG. 10 is another use state view thereof.

The broken lines shown in the drawings illustrate portions of the case for stylus pen that form no part of the claimed design.
